United States Patent Office.

WILLIAM L. McDOWELL, OF PHILADELPHIA, PENNSYLVANIA.

Design No. 2,711, dated July 23, 1867.

DESIGN FOR THE PLATES OF A STOVE.

The Schedule referred to in these Letters Patent and making part of the same.

TO ALL WHOM IT MAY CONCERN:

Be it known that I, WILLIAM L. McDOWELL, of the city of Philadelphia, in the State of Pennsylvania, have invented or produced a new and original Design for Stove-Plates, of which the following is a full, clear, and exact description, reference being had to the accompanying drawings, making a part of this specification, in which—

Figure 1 is a perspective view of several of the said plates applied to a stove, and

Figure 2 a transverse section of the design—

Like letters indicating the same objects in both figures.

This design consists of a raised panel, A B, having a raised oval, c, in the middle of a flat plane, d, which is raised a little above another plane, e, which forms the boundary of the design, as shown in the drawings.

What I claim as my invention or production, and desire to secure by Letters Patent, is—

The design for stove-plates herein set forth and shown.

WM. L. McDOWELL.
